ELECTRICAL DISCHARGE DEVICE

Ralph Harry Williams, Danvers, Mass., assignor
to Sylvania Electric Products Inc., Salem, Mass.,
a corporation of Massachusetts

Application June 19, 1943, Serial No. 491,742

3 Claims. (Cl. 176—122)

1

This invention relates to discharge devices and has particular reference to electrodes therein.

An object of this invention is to provide improved electrode formation and arrangement in discharge devices.

Another object is to provide an improved fluorescent lamp.

Another object is to provide an improved "bulb-type" fluorescent lamp.

Further objects, advantages and features will be apparent from the following specification taken in conjunction with the accompanying drawing, in which:

Figure 1 is a perspective view of a lamp embodying this invention;

Figure 2 is an enlargement of Figure 1, broken and cut away to show the electrodes and their leads;

Figure 3 is a view of the electrodes of Figure 2 showing the form of anode and the positional relation between anode and cathode; and

Figure 4 is a schematic operating wiring diagram of the lamp of Figures 1-3.

While this invention may readily be used in a variety of discharge devices, the illustrative embodiment herein shown and described comprises a small fluorescent bulb in dimension of the order of one inch by two inches and designed for use on low voltage D. C. of the order of 20 to 30 volts. This bulb contains argon and mercury and has an anode and a cathode for supporting an electron discharge. This discharge activates a coating of fluorescent material on the bulb, and the coating gives off ultra violet rays.

A particular use for this lamp is in so-called "black-light" arrangements wherein the visible rays from the lamp are filtered out and the ultra-violet rays are used to activate visible ray emanating fluorescent material on an object, for example, the dial of an instrument.

Accordingly, the particular lamp in illustration utilizes an argon, mercury and fluorescent material combination designed to produce a maximum of ultra violet radiation and a minimum of visible rays. Other combinations may be used as desired, for example, to produce a maximum of visible rays.

This bulb may be simply and easily mounted in or removed from a socket, just as an incandescent bulb may be handled. In addition it has quick and easy starting characteristics particularly at low voltage, high ultra violet output, and more uniformity and better distribution of arc field and ultra violet emanation around the cathode.

2

As in Figure 1, the lamp comprises a bulbous glass envelope 1, mounted on a brass base sleeve 2 with electrode lead contacts 3 and 4 held in an insulation body 5 which may be glass or other suitable insulation. A third electrode lead contact 6 connects with the base sleeve 2. The sleeve 2 has brass pins 7 extending outward for use in mechanically and electrically mounting the lamp in a socket, as for example in a bayonet type connection.

In Figure 2 the anode lead 8 and the cathode leads 9 and 10 are shown sealed in the flare sleeve 11 and extending to their respective contacts 3, 4, and 6. Mounted on these leads are the cathode 12 and the anode 13. Tube 14 is for evacuation of the bulb, and for the introduction of argon and mercury.

The cathode 12 is a coiled-coil type of tungsten filament coated with barium-strontium oxides as electron emissive material, heated to emission by current through the filament; the anode 13 is of molybdenum; and, as shown, the anode is in a plane substantially at right angles to the plane of the filament. The action of the lamp is to heat the cathode to emission and then the filament circuit is broken externally of the lamp to induce a discharge from the filament to the anode.

Figure 3 illustrates the arrangement of the anode 13 and cathode 12 with respect to each other. The cathode extends within and through the anode loop so that the anode extends completely around the cathode. The anode 13 is formed as a vertical, closed loop, relatively large at the top and relatively small at the bottom. Within this loop, the cathode 12 is preferably located adjacent the top, or large portion, for easy starting characteristics, as indicated by arrows 15; and relatively distant from the bottom, or small portion for long arc, high output characteristics as indicated by arrows 16. While the anode loop is referred to as closed, it may be open to the extent of being broken at one point while remaining effectively completely surrounding the cathode.

The cathode may, if desired, be located elsewhere in the anode loop, the controlling characteristic being that it is effectively surrounded by the anode loop. It is preferably located near the loop in one direction, and distant from the loop in another direction.

Thus, from whatever point on the cathode the arc emission originates, it may travel direct to the anode in an effectively straight line.

As an alternate structure, the anode 13 may be

supported from one of the leads of the cathode 12, to provide a two contact bulb instead of the illustrated three contact bulb.

In a lamp of this nature the anode must have sufficient surface area to carry the current. A large diameter loop may not be used since the anode must be assembled by insertion through the small neck of the bulb. A flat wire may not be used since it would have an undesirable shadow effect.

Thus the anode of this invention is particularly adapted for the lamp. The wire is of small area cross-section to avoid the shadow effect, the loop has a small lateral dimension to permit entry thereof through the neck of the bulb, and is elongated to provide the surface area necessary to carry the current.

What I claim is:

1. A fluorescent lamp for low voltage direct current operation comprising a small bulbous glass envelope with a reduced neck leading to the only entrance to the lamp; and an anode and a cathode extending into said lamp through said entrance and neck; said cathode comprising a filamentary electron emissive member extending 20 transversely of the lamp between a pair of uprights; and said anode comprising an elongated loop of small area cross-section mounted on a single support beneath said cathode and extend-

ing longitudinally of said lamp in a plane substantially perpendicular to the plane of said cathode and its supports, in such a manner as to contain said cathode adjacent the end of the anode loop furthest in the lamp.

2. A fluorescent lamp constructed for negative glow operation comprising a small envelope of bulbous form having a reduced neck portion, a base secured to its neck portion, a pair of lead wires extending into the envelope from said base, a substantially straight filamentary electron emissive cathode extending transversely of the envelope and secured at its ends to said lead wires, an anode comprising a flat elongated loop of wire presenting an upper portion circular in form and disposed concentric with and in a plane perpendicular to said cathode the remaining portion of the anode being relatively distant from the cathode extending toward and supported from said base.

3. A fluorescent lamp of bulbous form having a single base presenting a pair of current supply contacts, an anode comprising a flat elongated loop of wire connected to one of said current supply contacts, a substantially straight cathode extending perpendicularly through said anode adjacent one end of said loop, and connected to the other of said current supply contacts.

RALPH HARRY WILLIAMS.
